UNITED STATES PATENT OFFICE.

MARTIN PEARSON, OF LOS ANGELES, CALIFORNIA.

PROPELLING AND SUSTAINING MEANS FOR AERIAL NAVIGATION.

1,082,481.

Specification of Letters Patent.

Patented Dec. 23, 1913.

Original application filed February 19, 1913, Serial No. 749,549. Divided and this application filed June 9, 1913. Serial No. 772,706.

To all whom it may concern:

Be it known that I, MARTIN PEARSON, a citizen of the United States of America, residing at Los Angeles, county of Los Angeles, State of California, have invented a certain new and useful Propelling and Sustaining Means for Aerial Navigation; and I do hereby declare the following to be a full, clear, and exact description of the invention, such as will enable others skilled in the art to which it appertains to make and use the same.

This application is a division of application filed February 19th, 1913, Ser. No. 15 749,549.

The invention relates to propelling and sustaining means for aerial navigation, and it may be said to consist in the provision of the novel and advantageous features and in 20 the novel and improved construction, arrangement, and combination of parts and devices as will be apparent from the description and claim which follow hereinafter.

Objects of the invention are to provide 25 novel and improved means of the nature specified which has a comparatively large lifting and sustaining capacity, is adapted to operate with a comparatively small degree of slip and is constructed to provide 30 sufficient supporting surface to sustain the apparatus to which it is applied in the event of the motive means failing to act, is connected to be driven by either one or both of two independent motors, is simple in 35 character, strong and compact in construction, comparatively light in weight, safe and easily controlled in use, and effective in action.

Other objects and the advantages of the invention will be apparent to those skilled in 40 the art from a consideration of the following description of the preferred construction embodying it, taken in connection with the accompanying drawings in which—

45 Figure 1 is a partly broken elevational view of the construction; Fig. 2 is an enlarged partly broken and sectional view taken on the line 2—2 of Fig. 1; Fig. 3 is a partly broken sectional view taken on line 50 3—3 of Fig. 1; Fig. 4 is a top plan view of the construction; and Fig. 5 is an enlarged fragmentary view taken on the line 5—5 of Fig. 2.

The frame 6—not fully shown—may consist of oppositely disposed uprights 7 and 8

connected by cross-bar 9, together with oppositely disposed uprights 10 and 11 arranged at right angles to the uprights 7 and 8 and connected by cross-bar 12; the upper end portion of the uprights 7, 8, 10 and 11 being preferably formed semi-circular and joined together at the apex. 60

The ring 13 provided with inwardly projecting flanges 14 and 15 is adapted to fit over the upper end portion of the frame 6 and is rotatably connected to the frame 6 by means of brackets 16 which are suitably affixed on the uprights 7, 8, 10, and 11, and have thereon horizontal rollers 17 adapted to contact with the ring 13 and also have 70 thereon vertical rollers 18 and 19 adapted to contact with the flanges 14 and 15.

The semi-parachutic screw propeller 20 consists of strips 21 having the lower end portion thereof arranged vertically and 75 suitably secured to the ring 13 and having the upper end portion thereof curved upwardly and extending outwardly and downwardly and suitably secured at their ends to the ring 22 which is of considerably greater 80 diameter than the ring 13; a covering of suitable fabric 23 being affixed on the upper portion of the strips 21. The strips 21 in each half part of the screw propeller 20 are preferably made successively of increased 85 length from opposite ends of a straight line passing through the center of the screw propeller thereby forming the two elevating and sustaining surfaces 24 each of which slopes gradually downwardly and decreases 90 in size from the forward portion 25 thereof to the rear portion 26 thereof; the smaller rear end portion of one of the surfaces 24 being adjacent to the larger forward end portion of the other surface 24. 95

The horizontal screw propeller 20 may be driven by either or both of the rotary motors 27 which are disposed opposite to each other on the cross-bar 12; the stationary shafts 28 of the motors 27 having one 100 end thereof mounted on brackets 29 suitably affixed on the uprights 10 and 11. The driving connections between the motors 27 and the horizontal screw propeller 20 may consist of upright shafts 30 mounted in bearings 31 and 32 on the uprights 10 and 11 and having on the upper end portion thereof pinions 33 in mesh with the teeth 34 on the ring 13 and having on the lower end thereof bevel pinions 35 in mesh with the 110

bevel pinions 36 at the ends of sleeves 37 which latter are rotatively mounted on the stationary shafts 30; the sleeves 37 having feathered thereon parts 38 adapted to be moved to engage with parts 39 which are affixed to the rotors of the motors 27—the parts 38 and 39 preferably being in the form of cone clutches. The parts 38 may be moved into or out of engagement with the parts 39 by means of levers 40 which are pivotally mounted on the cross-bar 12 and have on the upper end thereof yokes 41 fitted in grooves in the parts 38; the lower end portion of the levers 40 having thereon handles 42 adapted to be locked in any desired position by means of pins 43 adapted to engage with the teeth of segmental gears 44 mounted on the cross-bar 12. The pins 43 may be operated by bell cranks 45 pivotally mounted on the handles 42. The central opening 46 in the horizontal screw propeller 20 permits a downward movement of air therethrough and thereby reduces the pressure of the air on the upper side of the propeller 20.

The mode of operation and advantages of the invention will be apparent to those skilled in the art from a careful consideration of the foregoing particular description of the construction, wherefore a more extended specification is deemed unnecessary in this case.

I claim:

In propelling and sustaining means for aerial navigation, a screw propeller consisting of a ring, a second ring arranged above and of greater diameter than the first ring, strips having the lower end portion arranged vertically and secured to the first ring and having the upper end portion thereof curved upwardly and extending outwardly and downwardly and secured at the outer ends thereof to the second ring, the strips in each half part of the screw propeller being successively of increased length as set forth, a covering of fabric affixed on the upper portion of the strips and forming the two elevating and sustaining surfaces 24 which slope downwardly and decrease in size from the front portion thereof to the rear portion thereof, the smaller rear portion of one of the surfaces 24 being adjacent to the larger forward portion of the other of the surfaces 24, substantially as described.

In testimony whereof, I have signed my name to this specification in the presence of two subscribing witnesses at Los Angeles, county of Los Angeles, State of California, this 2nd day of June A. D. 1913.

MARTIN PEARSON.
